UNITED STATES PATENT OFFICE.

MICHAEL CONINGSWOOD, OF CLIFTON, NEW JERSEY.

LOOM HARNESS MECHANISM.

Application filed November 26, 1926. Serial No. 150,806.

My invention relates to improvements in loom-harness mechanism.

The principal object of my invention is to provide a simple and convenient means for operating loom-harness for plain or fancy fabrics.

In the art of textile weaving, it is desirable to so operate the loom-harness as to lift the frames in irregular succession, the speed of travel of the respective harness frames not being uniform each with the other but in the course of their travel the speed of some will be greater than others. It being desirable that the speed be varied to meet the requirements of the art and the work to be performed, and that all of the harness frames be brought to a uniform plane at the terminus of travel.

I am aware that various mechanism has been heretofore devised to regulate and control the operation of the loom-harness and it is an object of my invention to simplify and improve the old devices and mechanism of the character described.

In the art, the loom-harness is suspended from the arch of the loom by cables or like medium which are carried over guide pulleys on the loom arch or frame and are connected with jacks or bell crank levers arranged adjacent the loom arch.

These jacks are caused to swing backward and forward thereby drawing up and lowering the loom-harness frames, which may be provided with springs adapted to normally draw down the frames, all of which is well understood and is old in the art.

An object of my invention is to provide means for regulating the speed of travel of the loom-harness and to vary and adjust the relative speed and operation thereof to the requirements of the art.

A further object of my invention is to provide in a loom-harness mechanism, a simple and convenient substitute for cam wheels and other intricate mechanism.

A further object of my invention is to provide a loom-harness mechanism of a minimum number of parts.

The accompanying drawings illustrate

one form in which my invention may be embodied but it is understood that the drawings are for illustration only and not to limit the invention and that the form shown may be modified and changed without departing from my invention.

In the drawings

Figure 1 is a view of the upper arch portion of a loom frame showing one of the operating levers or jacks, the loom-harness and connecting medium with my improved invention associated therewith.

Figure 2 is a detail of the same, but showing two jacks and frames,

Figure 3 is a detail showing an arrangement of the connecting strips and pulleys,

Figure 4 is a view of one of the connecting strips and its cam member, and

Figure 5 is a section on the line 5—5 in Figure 4.

Similar characters of reference refer to similar parts throughout the several views.

In the drawings I have shown on the arch 1 of a textile loom a shaft carrier 2 in which is mounted a shaft 4, provided with a plurality of spaced idler pulleys 5, 6, 7, 8 and 9.

At one side of the loom adjacent the arch 1, are provided operating levers or jacks 10, 11 of the usual type.

The harness-frames 12, 13 are suspended from cables 14, 15 respectively which are carried over guide pulleys 16, 17 positioned on the arch of the loom.

My improved device, includes a narrow plate or strip of steel or the like 18 provided on its face or upper surface with a cam block 19 preferably having a lug 20 adapted to be adjustably positioned in a slot 21, in the plate 18 and secured thereon by set screws 22.

The cables 14, 15 by which the harness-frame 12, 13 are respectively supported, are connected to one of the ends of the strips 18 by means of a perforation 24 therein and the strip 18 is connected at its other end to a jack 10 by a perforation or slot 25, whereby the strip 18 is incorporated in and forms a part of the medium connecting the harness frame and its jack.

The strip 18 is positioned below and passes underneath a loose idler or roller 5 on the shaft 4.

In the operation of the loom, the jack is caused to rock as above explained and thus draws the cam block 19 on the strip 18 backward and forward under the idler 5, with which the cam block 19 contacts.

As the block 19 passes under and in contact with the pulley or idler 5, the strip 18 will be depressed, thus shortening the distance between the harness-frame 12 and the jack 10, whereby the movement of the harness-frame will be accelerated in its ascent and retarded in its descent during the period when the cam block is engaged by its idler, and when disengaged, the travel will be restored to normal.

The size and shape of the cam blocks 19 may be varied and modified as desired and as the work to be performed may require, thereby causing corresponding variations in the movement of the harness-frames controlled thereby.

I have shown in section in Figure 3, a plurality of cam blocks 19, 19¹, 19², 19³, 19⁴ of progressively graduated size, each engaged by its idler 5, 6, 7, 8 and 9 respectively, with neutral bands or strips 26, 26¹, 26², 26³, 26⁴ between these spaced idlers but this arrangement may be varied as desired and as conditions may require.

Having thus described my invention, what I claim is:

35. 1. In a device of the character described the combination of a harness-frame, a jack, a connecting medium operatively connecting the harness frame and the jack, a cam block on the connecting medium and a pulley adapted to engage the cam block whereby in the longitudinal movement of the connecting medium the pulley will be engaged by the cam block producing a transverse movement of said camp block and connecting medium so that the harness-frame is moved farther than it would be with straight line motion of the connecting medium.
40. 2. In a loom, the combination of a jack and a harness frame, a connector operatively connecting the jack and the harness frame, a cam block on the connector and a member adapted to contact with the cam block whereby in the longitudinal movement of the connector a transverse movement of said connector will also be produced so that the harness frame is moved farther than it would be with straight line motion of the connector.
45. 3. In a loom, the combination of a jack and a harness frame, a connector operatively connecting the jack and the harness frame, a cam block adjustably positioned on the connector and a member adapted to contact with the cam block whereby a transverse movement of the connector is produced during its longitudinal travel so that the harness

frame is moved farther than it would be with straight line motion of the connector.

4. In a loom, the combination of a jack and a harness frame, a slotted connector therebetween, a cam block adjustably positioned on the connector and a member adapted to contact with the cam block whereby in the longitudinal movement of the connector the last named member will be engaged by the cam block producing a transverse movement of said cam block and connector so that the harness frame is moved farther than it would be with straight line motion of the connector.

5. In a loom, the combination of a jack, a harness frame adapted to be driven thereby, a connector between the jack and the harness frame and including a strip and a cam block thereon, and a roller adapted to contact with the cam block whereby in the longitudinal movement of the connector the roller will be engaged by the cam block producing a transverse movement of said cam block and connector so that the harness frame is moved farther than it would be with straight line motion of the connector.

6. In a loom, the combination of a loom frame and a harness frame, a jack on the loom frame, a pulley intermediate the jack and the harness frame, a connector between the jack and the harness frame and a cam on the connector adapted to contact with the pulley whereby in the longitudinal movement of the connector, there will be produced a transverse movement of the connector and cam block so that the harness frame is moved farther than it would be in the straight line movement of the connector.

7. In a loom, the combination of a shaft, a plurality of spaced idlers on the shaft, a plurality of jacks, a plurality of loom harness frames adapted to be operated by the jacks, connectors between the jacks and the frames, and cam blocks on the connectors and adapted to contact with the idlers whereby in the longitudinal movement of the connectors, there will be produced a transverse movement of the connectors and cam blocks thereon so that the harness frame is moved farther than it would be in the straight line movement of the connectors.

8. In a loom, the combination of a harness and a jack, a connector therebetween, a cam on the connector, and a fixed roller adapted to contact with the cam so that in the longitudinal movement of the connector the fixed roller will be engaged by the cam producing a transverse movement of said cam and connector so that the harness is moved farther than it would be with straight line motion of the connector.

9. In a device of the character described, the combination of a loom, a loom arch thereon, a shaft carried by said arch, an idler pulley on said shaft, a jack, a harness

frame, a cable connecting said jack and said harness frame, guide pulleys for said cable, a flat strip of material on said cable intermediate said jack and said harness frame, a cam block on said flat strip of material, a roller adapted to contact with said cam block in the longitudinal movement of the

said strip whereby the harness frame is moved farther than it would be in the straight line movement of the said strip. 10

In testimony whereof, MICHAEL CONINGS-
wood has signed his name to this specifica-
tion, this 10th day of November, 1926.

MICHAEL CONINGSWOOD.
